PANEL OR THE LIKE

Edward E. Saathoff, North Hollywood, Calif.
Application March 4, 1957, Serial No. 45,100

Term of patent 14 years

(Cl. D13—1)

The panel is broken away in the center portions thereof to indicate indeterminate length.

I claim:

The ornamental design for a panel or the like, substantially as shown and described.
